UNITED STATES PATENT OFFICE.

WILLIAM W. POTTS, OF SWEDELAND, PENNSYLVANIA.

DESIGN FOR A DRESSING-CHAIR.

SPECIFICATION forming part of Design No. 32,714, dated May 22, 1900.

Application filed April 24, 1900. Serial No. 14,196. Term of patent 14 years.

To all whom it may concern:

Be it known that I, WILLIAM W. POTTS, a citizen of the United States, residing at Swedeland, in the county of Montgomery, State of Pennsylvania, have invented and produced a new and original Design for Dressing-Chairs, of which the following is a specification, reference being had to the accompanying drawing, forming part thereof.

The leading feature of my design for a dressing-chair is a chair having back members of the form of clothes-trees.

The figure represents a perspective view of a dressing-chair embodying my design.

In the drawing, A designates the seat of a dressing-chair, and B the back thereof, said back comprising clothes-trees composed of the columns C and pegs D. The seat A is of box form and upholstered.

Having described my invention, what I claim as new, and desire to secure by Letters Patent, is—

The design for a dressing-chair substantially as shown and described.

WILLIAM W. POTTS.
